United States Patent Office.

JAMES S. WATERS, OF ST. LOUIS, MISSOURI, ASSIGNOR TO ST. LOUIS LEAD AND OIL COMPANY.

Design No. 3,044, dated May 12, 1868.

DESIGN FOR A TRADE-MARK.

The Schedule referred to in these Letters Patent and making part of the same.

TO ALL WHOM IT MAY CONCERN:

Be it known that I, JAMES S. WATERS, of St. Louis, in the county of St. Louis, and State of Missouri, have invented a new and original Design for a Trade-Mark, of which the following is a full, clear, and exact description, reference being had to the annexed drawing, making a part of this specification.

It consists of a square ornamental border of scroll-work, surrounding the words "Washington White-Lead Co.—Pure Lead." This is to be used as an engraving or print, and is of different colors. This may also be used as a brand, and, when so used, the various parts will have such breaks in them as may be necessary to give the requisite strength to the stencil or other plate by which the impression is made.

What I claim as my invention, and desire to secure by Letters Patent, is—

The design for a trade-mark, as shown and specified.

JAS. S. WATERS.
